Albert Freundlich, New York, N. Y., assignor to
 Kamket Corporation, New York, N. Y., a corporation of New York

Application June 11, 1938, Serial No. 213,149

2 Claims. (Cl. 281—25)

This invention relates to a book and particularly to book constructions, the individual sheets whereof are independent of each other but bound together to form a book. The book when open will lie absolutely flat and the individual pages thereof will be accessible substantially from edge to edge. The amount of material along the bound edge which is utilized for associating the pages in their book formation need not exceed a quarter of an inch and preferably approximately three-sixteenths of an inch, but nevertheless securely uniting the sheets into book formation. This invention is particularly useful in connection with binding together catalogs, circulars, and photo-prints of printed or written matter, which are usually printed upon fairly heavy paper and often bear printed or illustrative matter close to the binding edges. It may also be utilized in connection with blank books which are provided for keeping memoranda or records, particularly entry books which are ruled from edge to edge.

The pages comprising the book are individual sheets but united by the binding element, which binding element, although permanently united with the pages, is, nevertheless, independently movable as the book is opened or closed, reducing the friction at the points where the sheets and the binder unite, thereby preserving the pages against tearing. The book as a whole is flexible and the binding element readily flexes with the book, particularly in a lengthwise direction, but readily resumes its normal position by reason of its special features of construction.

The binder of this invention is exceedingly strong and not readily deformable permanently during the ordinary use of the book and the entire binder, if flexed, will readily return to its normal shape, tending to support the book as a stiffening element and not being subject to permanent deformation by use in handling and when the book stands on edge.

In the drawing, Fig. 1 represents a book comprising a multiplicity of sheets bound together with the binder element of this invention; Fig. 2 is a cross section on the line 2—2 of Fig. 4; Fig. 3 is a side view of a portion of the book and binder from the left of Fig. 1; Fig. 4 is an enlarged view from the top of Fig. 1; Fig. 5 is an enlarged view of one of the page-supporting elements and portions of the diverging tie rods; Fig. 6 is a section on the line 6—6 of Fig. 2.

A bound book comprises a multiplicity of pages 1, provided with holes 2 along the binding edge of the book. The holes 2 may be of any desired shape preferably rectangular or oval. The binder

3 is associated with the book by threading the pages into the page-supporting elements of the binder. The binder 3 comprises a multiplicity of fastener elements 4, spaced apart a suitable distance and united with the tie rods 5. Each fastener element 4 consists of two members 6 and 7, formed on the arc of a circle, flat from the point 8 of divergence, from the tie rod, to the tip 9 of the fastener members 6 and 7. The free ends of each pair of fastener members 6 and 7 are joined by the tip or nose 9, which, at its extreme end 10, is rounded and narrower than the distance across the fastener members 6 and 7. Each pair of fastener members, as illustrated in Figs. 5 and 6, has the appearance of being made of a single length of flat stock but actually the fastener members comprise two separate sections of material lying quite closely together. It is preferred to have the inside edges of the two members 6 and 7 in contact, but there is a tendency for these members to separate slightly in use. The fastening elements do not comprise a complete circle but, to the contrary, extend only from the point 8 to the base of the tip 9. The fastening elements 6 and 7 terminate at the point of divergence 8 and adjoining fastening members are united together by the tie rods 5 comprising a single course of metal, round in cross section, as shown at 11 in Fig. 2. If desired, the tie rods may be bent in a slight arc, as shown in Fig. 5, to provide a space 12 which permits the tip 9 to be brought quite close to the surface of the tie rods, as is illustrated in Fig. 5.

The individual pages of the book are threaded over the rounded tip 9 and ultimately over the body of the fastener members 6, 7. This may be done while the tip 9 is spaced some distance from the tie rods 5 and thereafter the fastener element is deformed to bring the tip 9 in close relation to the tie rods.

The binders are preferably made initially of round wire and after the elements are formed but while still in the flat condition, the fastener elements 6 and 7 are flattened either by a pinching or stamping operation on an anvil or by other suitable tools. The flattening operation is so conducted that neither the tie rods 5 nor the tip 9 are flattened. During the course of the flattening operation the otherwise slightly flexible and readily bendable wire is compacted and strengthened.

I claim:

1. A book comprising a multiplicity of pages having a series of holes along the binding edge thereof, a binder, said binder being made of a single length of continuous metal formed to pro-

vide a multiplicity of sets of ring-like binding elements, opposite binding elements being united by tie rods, each binding element comprising flattened duplex portions extending substantially from the terminus of their tie rods to the free end of the ring-like binding member, each flattened portion comprising each ring-like member having their inside edges normally lying against one another, the extreme free end of the flattened duplex members being united by a nose forming an inserting tip, said nose being formed of metal substantially circular in cross-section and having its most forward edge rounded, the ring-like

members of the binder passing through said holes in said pages.

2. A book according to claim 1, in which the nose of the binding element is narrower than the distance across the flattened portions of the duplex ring-like members and the tie rods associated, with each flattened portion, diverging in opposite directions from the flattened portions and forming a space for the entry of the extreme end of said nose to secure the pages of the book from escape from said binder.

ALBERT FREUNDLICH.
